PERFORATOR

Filed May 20, 1929

UNITED STATES PATENT OFFICE

HAROLD U. BAKER, OF LOS ANGELES, CALIFORNIA, ASSIGNOR OF THREE-EIGHTHS TO
ELMORE D. JONES, OF LONG BEACH, CALIFORNIA, AND THREE-EIGHTHS TO WIN-
FIELD S. JONES, OF BREA, CALIFORNIA

PERFORATOR

Application filed May 20, 1929. Serial No. 364,420.

This invention contemplates an improvement upon the invention of Winfield S. Jones and the present inventor for perforators, patented in the United States September 25, 5 1928, No. 1,685,492. In said patent, we described a perforator having certain novel features whereby a cutter blade was released when the perforator was positioned at a desired point within the casing, and which 10 cutter blade was adapted to perforate the said casing when so positioned. The present invention contemplates a perforator so arranged and constructed as to allow the ready perforation of casing at any zone desired and with minimum effort. With respect to the above, when a well hole is of 15 great depth, a turning of the stem carrying the cutter tends to "cork screw" the said stem, particularly when pressure is exerted 20 downwardly upon the stem. This motion is analogous to stretching a thin wire across a room and then attempting to push upon the wire so as to force some object through another object at the opposite end of the wire. 25 This might be accomplished but could only be accomplished with difficulty and the same is true when pressure is exerted upon a stem in a well hole so as to force a cutter through casing many thousand feet from the surface 30 of the well hole.

The present invention has for an object a novel means whereby cutters may be forced through the casing without fear of endangering the stem.

35 Other objects of the invention include a device which is simple of construction, easy to operate, little fear of injuring the cutting tool or damaging the stem, and which is generally superior in use and serviceability.

40 With the above mentioned and other objects in view, the invention consists in the novel and useful provision, formation, construction, association and relative arrangement of parts, members and features, all as 45 shown in a certain embodiment in the accompanying drawings, described generally, and more particularly pointed out in the claims.

50 In the drawings:

Figure 1 is an elevation of the improved perforator as an entirety,

Figure 2 is a longitudinal sectional view of the improved cutter,

Figure 2a is a continuation of Figure 2,

55 Figure 3 is a cross sectional view on the line 3—3 of Figure 2, and,

Figure 4 is a cross sectional view on the line 4—4 of Figure 2.

Referring to the drawings, in order to properly describe this cutter, certain of the notations and description given in Patent No. 1,685,492 will again be included, although for fuller explanation, reference is had to said patent.

Referring with particularity to the drawings the improved perforator is designated as an entirety by A, and the same includes a body a, a member b movable relative to the body, gripping means c and d, a cutter e, 70 and means f for actuating the cutter, all of which elements are used in practicing one embodiment of the present invention. The body a is formed at one end with a circular chamber or bore 1, and likewise provided 75 with screw-threads 2. Adapted to be received in part within said bore 1 is a mandrel 3 constituting a part of the actuating means f for the cutter e. This plunger is formed with a head 4 and a stem or arm 5, 80 the stem or arm 5 being substantially circular, and passed through a guide bushing 6 in threaded engagement with the threads 2. The cutter e is arcuate or curved and adapted to be fitted within a curved bore 7 which communicates with the bore 1 and externally of the body a, as shown at 8. The cutter blade is secured to the mandrel by means of a link 9, which link is pivoted respectively to the mandrel head 4 and an end of the cutter blade 90 as indicated at 11 and 10. The cutter blade is formed with a substantially sharp or pointed object-engaging nose 12. Thus, if the mandrel was allowed movement, the cutter blade would reciprocate within the curved bore 7 outwardly of the body and inwardly thereof. The cutter body is reduced as to diameter at the end opposite the chambered end 1, as shown at 13, and the member b which constitutes in reality a sleeve is mov-

- able upon such reduced end. The said sleeve is provided with a base portion 14 having a central bore 15. The body *a* at the reduced end portion is recessed at 16 to in part confine 5 a latch 17 pivoted to said body at 18 and the said latch has a notched end 19. The member *b* is slotted at 20 so that the said latch may when in one position, as shown in Figure 2*a*, engage an end wall 21 bounding said slot 10 20. The body *a* is formed to carry one or more of the slips *d*, and the body to this end is formed with a plane surface 22 which is at an angle to the outer surface of the body. This construction forms a ledge 23. A bore 15 24 is passed through the body at the ledge portion 23 and adjacent the portion of reduced diameter of said body. The slip *d* is substantially wedge-shaped and is adapted to be substantially flush with the outer surface 20 of the body when the same is fitted against the inclined wall 22, as shown in the figures. An arm 26 is passed through said bore 24, and connected to the slip *d*. The opposite end of said arm is secured to the sleeve *b*, by providing said arm with an angular extremity 27 received in a transverse bore 28 of the sleeve. Adapted to be fitted within the member *b* and likewise slidable therein, is a head 29, and joined 25 with said head is a mandrel 30, the shank portion of which is passed through the bore 15 in the base of the sleeve. Carried on this mandrel and slidable thereon is the friction spring member *c* which includes two spring 30 arms 31 and 32 which are secured to top and bottom collars 33 and 34, which collars are carried on the mandrel. The said member *c* is prevented from escape from the mandrel in any suitable manner, such as by a nut 35 40 screw-threaded upon an end of the mandrel. To maintain the various parts in association, as shown in Figure 2*a*, a frangible pin 36 is passed through the stem 3, and which pin will bear against the top surface of the nut 45 6 secured to the body, and thus hold the plunger elevated and maintain the cutter within the bore 7 of the body. Likewise a frangible pin is passed through aligned bores 37 in the sleeve *b* and the head 29, whereby 50 the mandrel is maintained in a certain position relative to said sleeve. The position is likewise such that the latch 17 is held so that the notch 19 bears against the head 29. The latch is kept in tight engagement with the 55 head and likewise the sleeve through the medium of a leaf spring 39 secured to the reduced portion of the body and bearing against the top edge of the said latch, as shown at 40.
- 60 More particularly, the present invention is directed to suitable means for boosting or increasing the pressure of the cutter against the casing. As was pointed out in the objects, oftentimes the mere weight of the stem 65 due to twist and the like thereof is insuffi-

cient to force the cutter through a casing, or the stem in damaged in the attempt to force the cutter through the casing. The present invention, by boosting the relative downward pressure permits the cutter to be operated without damage to the stem. This particular means is designated as *f* and the same includes that portion of the device shown in Figure 2 and above the bushing 6. The mandrel 3 is passed through the bushing 6 and carries at its upper end a piston head 41. This piston head includes a substantially circular piece mounted upon the mandrel and provided with two portions of reduced diameter 42 and 43, all portions being arranged concentrically. The portion 43 is screw-threaded at 44. This piston head is within an elongated cylinder 45, one end of which cylinder is screw-threaded to the bushing 6, as shown at 46. Surrounding the portion 42 of the piston head is a packing member 47 and screw-threaded to the threads 44 of the portion 43 of the piston head is a sleeve 48. The end of the sleeve where it is screw-threaded to the part 43 is adapted to bear against a washer 49 which in turn bears against the packing piece to hold the same in position on the piston head 41. This sleeve 48 is confined within the cylinder 45 and said sleeve is transversely and diametrically slotted, as shown at 50. Furthermore, the periphery of the sleeve is slightly spaced from the inner wall of the cylinder. The upper end of said cylinder is screw-threaded to a bushing 51, which bushing in turn is screw-threaded to a tubular member 52. Adapted to be passed through the tubular member 52, bushing 51 and into the sleeve 50 is a plunger 53. A member 54 is passed transversely through the plunger at 55 and is received within the transverse slot of the sleeve 50. This plunger is provided with an annular flange 56, which flange is slightly less in diameter than the inner diameter of the tubular member 52. The tubular member 52 is adapted to have screw-threaded at the upper end thereof a cap nut 57. Likewise said tubular member is provided with an internal annular flange 58 near the opposite end of said tubular member. The bushing 51 is provided with a port 59 which will allow communication externally of the bushing and internally of the cylinder 45. The bushing 6 is provided with ports 60 and 61 which inter-communicate and likewise permit communication within the cylinder 45 and the bore 1 of the cutter body *a*. The bushing 51 is likewise centrally bored to house a packing and gland 62 and 63 respectively. The plunger 53 exteriorly of the tubular member communicates with the drill stem 64.

The operation, uses and advantages of the invention just described are as follows:

If it is desired to perforate the casing and

assuming that the slips are engaging the casing to hold the body in a given position so that the cutter may be urged outwardly from the body for casing engagement, then said cutter would be actuated as follows: Downward movement of the stem 64 will cause downward movement of the plunger 53. The cylinder 45 has been first filled with oil or grease through the port 59 after which said port is plugged and downward movement of the plunger 53 will cause a compression of the oil within said cylinder. This pressure will be communicated by the oil or grease against the piston head 41 and the piston head upon movement will move the mandrel 3 which will, of course, cause movement of the cutter. The cross sectional area of the head of the plunger acting within the slotted sleeve 50 is considerably less than the cross sectional area of the top of the piston head 41 and thus a differential pressure and stroke is the result. The openings 60 in the bushing permit ready escape of any oil back of the piston head into the bore 1, and thus back pressure is overcome. When it is desired to retract the cutter, the stem may be moved upwardly which will in turn move the plunger upwardly. The member 54 will carry the sleeve when it contacts with the head of said sleeve and elevate the sleeve, it being remembered that this sleeve is secured to the piston head and, of course, upward movement of the piston head would raise the mandrel connected with the cutter. Movement of the plunger is arrested when the flange 56 strikes the cap on the end of the tubular member 52. This form of device is very efficient in operation and assures that undue strain on the working parts of the device is effectively prevented. It is possible to position the perforator anywhere desired within the casing and then, with less pressure than would be ordinarily required if the differential or booster system is not utilized, cause said cutter to pierce the casing.

It is to be particularly noted that the sleeve does not fit tightly within the cylinder nor does the plunger fit tightly within the sleeve.

Thus, when the plunger moves downwardly within the sleeve, the fluid within said cylinder and sleeve is forced downwardly and likewise permitted to flow upwardly around the plunger and likewise into the space included between the sleeve and the inner wall of the cylinder.

For further details concerning a cutter of this type, reference is again directed to the patent heretofore mentioned.

It is obvious that various changes and modifications and variations may be made in practicing the invention in departure from the particular showing of the drawings and description as given without, however, departing from the true spirit of the invention.

I claim:

1. A perforator adapted to be placed within a casing including a body, a cutter carried thereby, and differential pressure means for actuating said cutter. 70
2. In a perforator adapted to be placed within a casing, a body, a cutter carried thereby, a piston for said cutter, and means for creating a differential pressure against said piston to actuate said cutter. 75
3. In a device of the character disclosed, a cutter blade, a piston head connected thereto, a cylinder for said piston head, and a plunger having a lesser cross sectional area than the cross sectional area of the piston head, said plunger being movable within said cylinder, and fluid means within the cylinder whereby differential pressure between the plunger and the piston head results when the plunger is moved to compress said fluid. 80
4. In a device of the character disclosed, a cutter blade, a piston head connected thereto, a cylinder for said piston head, a plunger having a lesser cross sectional area than the cross sectional area of the piston head, said plunger being movable within said cylinder, and fluid means within the cylinder whereby differential pressure between the plunger and the piston head results when the plunger is moved to compress said fluid, in combination with means for limiting movement of said plunger in two directions. 85
5. In a perforator, a cylinder, a piston head therein, a slotted sleeve within said cylinder and secured to said piston head, a plunger within said sleeve, said cylinder being adapted to confine a fluid, and whereby movement of the plunger within the sleeve creates a differential pressure against said piston. 90
6. In a perforator, a cylinder, a piston head therein, a slotted sleeve within said cylinder and secured to said piston head, a plunger within said sleeve, said cylinder being adapted to confine a fluid, and whereby movement of the plunger within the sleeve creates a differential pressure against said piston, in combination with means for limiting movement of said plunger within said sleeve. 95
7. In a perforator, a cylinder, a piston head therein, a slotted sleeve within said cylinder and secured to said piston head, a plunger within said sleeve, said cylinder being adapted to confine a fluid, and whereby movement of the plunger within the sleeve creates a differential pressure against said piston, in combination with a cutter joined with said piston head for guiding movement of said cutter when the piston head is moved. 110
8. In a device of the character disclosed, a cutter blade, a piston head connected thereto, a cylinder for said piston head, and a plunger having a lesser cross-sectional area than the cross-sectional area of the piston head. 125
- 130

9. In a device of the character disclosed, a cutter blade, a piston head connected thereto, a cylinder for said piston head, and a plunger having a lesser cross-sectional area than the cross-sectional area of the piston head, said cylinder being adapted to house a fluid and whereby when the plunger is moved within said cylinder, a differential pressure between the plunger and piston head results.
10. In testimony whereof, I have signed my name to this specification at Los Angeles, California, this 25th day of January, 1929.

HAROLD U. BAKER.
